UNITED STATES PATENT OFFICE

93,715

DESIGN FOR A VANITY CASE OR SIMILAR ARTICLE

Herbert H. Harris, New York, N. Y.

Application September 6, 1934, Serial No. 53,215

Term of patent 14 years

To all whom it may concern:

Be it known that I, HERBERT H. HARRIS, a citizen of the United States and resident of New York, in the county of New York and State of New York, have invented a new, original, and ornamental Design for a Vanity Case or Similar Article, of which the following is a specification, reference being had to the accompanying drawing, forming part thereof.

In the drawing:

Fig. 1 is a perspective view of a vanity case showing my new design.

Fig. 2 is a rear face view thereof.

Fig. 3 is an edge view of the same.

I claim:

The ornamental design for a vanity case or similar article, substantially as shown.

HERBERT H. HARRIS.

DISCLAIMER

Des. 93,715.—Herbert H. Harris, New York, N. Y. A VANITY CASE OR SIMILAR ARTICLE. Patent dated October 30, 1934. Disclaimer filed May 14, 1936, by the patentee.

Hereby disclaims the subject-matter of the claim of the said Letters Patent, except when the design covered by such claim includes the ornamentation of the surface of the article embodying the design, substantially as shown in Figure 1 of the drawings of said Letters Patent.
